UNITED STATES PATENT OFFICE.

OREN C. DODGE, OF BROOKLYN, NEW YORK.

IMPROVEMENT IN CONSTRUCTION OF WOODEN BUILDINGS.

Specification forming part of Letters Patent No. 124,344, dated March 5, 1872.

To all whom it may concern:

Be it known that I, OREN C. DODGE, of Brooklyn, in the county of Kings and State of New York, have invented an Improvement in the Construction of Wooden Buildings; and the following is declared to be a correct description thereof:

Wooden buildings have heretofore been made with air-spaces between the clapboarding, the studding, and the plastering, and these air-spaces have sometimes been subdivided by lath and plastering between the studding. This is expensive, and, the plaster being porous and liable to crack, does not make a reliably warm house. Paper and tarred paper and felt have also been employed between two layers of boarding.

My invention is intended for rendering the house warmer in winter and cooler in summer, in consequence of the use of two air-spaces between the outer planking and inside plaster, said air-spaces being made by a sheet of felt or similar material passing diagonally across the space between the planking and plaster from the outer side of one of the posts or studs to the inner side of the next; thereby a cheap and tight division will be made that prevents air blowing through the outer walls of the house, and confines the non-conducting air in two prismatic receptacles made of the afore-

said parts, and prevents the transmission of heat in summer or cold in winter.

In the drawing, Figure 1 is a sectional plan of the said improvement, and Fig. 2 is a perspective view of the same.

Upon the sill *a* the usual studding or posts *b* are erected, and before the clapboarding or sheathing *c* is applied, or the lathing or interior wall *d* is attached, the sheets of felt or tarred paper *f* or similar material are secured to the studs or posts *b*, the same being fastened to the outside of one stud and to the inner side of the next. In this manner the spaces between the studs are divided into two air-chambers for the purposes aforesaid.

I prefer to attach the sheets *f* at the top and bottom by cleats *i* or strips nailed to the sills and timbers at the top and bottom ends of the studding.

I claim as my invention—

The sheets *f*, of paper, felt, or similar material, introduced diagonally between the studs *b*, and attached at the outer side of one stud and the inner side of the next, for the purposes set forth.

Signed by me this 25th day of January, 1872.

Witnesses: OREN C. DODGE.
